CLAIM

The ornamental design for an equipment cover, as shown and described.

DESCRIPTION

FIG. 1 is a front, right, top perspective view of an embodiment of an equipment cover showing my new design; FIG. 2 is a first enlarged partial perspective view thereof, as indicated in FIG. 1;

FIG. 3 is a second enlarged partial perspective view thereof, as indicated in FIG. 1;

FIG. 4 is a rear, right, bottom perspective view thereof; FIG. 5 is an enlarged partial perspective view thereof, as indicated in FIG. 4;

FIG. 6 is a rear, left, bottom perspective view thereof;

FIG. 7 is a front, left, top perspective view thereof;

FIG. 8 is an enlarged partial perspective view thereof, as indicated in FIG. 7;

FIG. 9 is a front elevation view thereof;

FIG. 10 is a rear elevation view thereof;

FIG. 11 is a left side view thereof;

FIG. 12 is a right side view thereof;

FIG. 13 is a top plan view thereof; and,

FIG. 14 is a bottom plan view thereof.

The broken lines of uneven length shown in the drawings form a boundary of the claimed design. The broken lines of even length shown in the drawings illustrate portions of the equipment cover that form no part of the claimed design.

1 Claim, 14 Drawing Sheets
